UNITED STATES PATENT OFFICE.

BUFORD J. STEEN, OF SAN ANTONIO, TEXAS.

SAFETY RAZOR.

Application filed June 26, 1925. Serial No. 39,830.

To all whom it may concern:

Be it known that I, BUFORD J. STEEN, a citizen of the United States, residing at San Antonio, in the county of Bexar and 5 State of Texas, have invented certain new and useful Improvements in a Safety Razor, of which the following is a specification.

This invention relates to new and useful improvements in a safety razor.

10 One object of the invention is to provide a razor of the character described formed to receive the conventional type of blade, now in common use, and embodying also means whereby the blade can be easily 15 sharpened without removal from the razor.

Another object of the invention is to provide a safety razor which is of simple construction, and may be cheaply produced and whose blades may be quickly and easily 20 sharpened when the same becomes dull.

With the above and other objects in view this invention has particular relation to certain novel features of construction, operation and arrangement of parts, an example 25 of which is given in this specification, and illustrated in the accompanying drawings, wherein:—

Figure 1 shows a front elevation.

Figure 2 shows an edge view with the 30 blade in position for sharpening.

Figure 3 is a cross sectional view taken through the handle.

Figure 4 shows an outer end view.

Figure 5 shows an edge view with the 35 blade in position for shaving and Figure 6 is a fragmentary rear view.

Referring now more particularly to the drawing, wherein like numerals of reference designate similar parts in each of the figures the numeral 1 designates the handle, one end of which is formed with a substantially rectangular head 2, whose outer surface is convex and formed with an abrading coat 3 of suitable sharpening material.

40 The handle is slotted lengthwise, as at 4, and this slit is formed into the two spaced, transverse bearings 5 and 6. At one edge the head has the short end extensions, or fingers 7, 7, and at its other edge the head 50 has similarly disposed end extensions which are retracted forming the catches 8, 8 and the respective ends of the head have the aligned notches 9, 9.

There is a frame designated generally by 55 the numeral 10. This frame has the side arms 11, 11 on opposite sides of the handle,

and which are connected by the cross rod 12, adapted to work in either bearing 5 or 6.

The free ends of these arms are configured to pass around the respective ends of the head and their extreme ends are inwardly turned forming studs 13, 13.

There is a blade holder 14, preferably formed of two ply metal whose free edges 65 coincide and fit closely together forming jaws 15, 16, between which the blade 17 is inserted. The blade has perforations 18 and one jaw is formed with detents 19 which fit through said perforations and into opposing 70 depressions or recesses in the other jaw. The other edge of the holder is formed cylindrical to provide a bearing 20 into whose ends the studs 13 fit.

In use for shaving purposes, the cross 75 rod 12 is located in the bearing 6, with the side arms 11 resting in the respective end notches 9 and with the ends of the operative edge of the blade engaged under the catches 8. In this position the razor may 80 be safely used for shaving.

When it is desired to sharpen the blade the frame is grasped and pulled outwardly to carry the cross rod 12 into the bearing 5. The opposing sides of the handle are flexible 85 and will yield, or bend, outwardly to permit this movement, and will spring back together when the cross rod is seated in said bearing. The ends of the blade holder may now be grasped and the blade swung back 90 and forth with its edge in contact with the abrading surface 3. The inner sides of the arms 11, have the notches 21, 21 which receive the respective ends of the head during this swinging movement. The sharpened edge 95 of the blade is held out of contact with the edges of the head, at the end of each stroke, in sharpening, by the fingers 7, and catches 8.

When the blade is sharpened the frame 100 may be forced back to original position, with the cross rod 12 in the bearing 6. The outer sides of the notches 21 are beveled so as to disengage the ends of the head therefrom to permit this movement of the frame, the 105 blade ends may be now again engaged under the catches 8 with the side arms in the end notches 9 and the razor will be again in position for shaving.

What I claim is:—

1. A razor including a handle formed with spaced bearings, a head carried by one

2
end thereof whose outer side is convex, a frame capable of movement into either of said bearings, and formed with side arms, a blade holder mounted between said arms, a blade mounted in and detachable from said holder.

2. A razor including a handle, formed with spaced bearings, a head carried by one end thereof whose outer side is convex, a frame capable of movement into either of said bearings, and formed with side arms, a blade holder mounted between said arms, a blade mounted in and detachable from said holder, said head having end bearings in which said arms are adapted to seat.

3. A razor including a handle formed with spaced bearings, a head carried by one end thereof whose outer side is convex, a frame capable of movement into either of said bearings, and formed with side arms, a blade holder mounted between said arms, a blade mounted in and detachable from said holder, said head having end bearings in which said arms are adapted to seat, and end catches carried by one edge of the head and adapted to receive the respective ends of the operative edge of the blade.

4. A razor including a handle formed with spaced bearings a head carried by one end of the handle whose outer surface is convex, spaced fingers carried by one edge of the head, spaced hooks carried by the other edge of the head, a frame formed with

side arms and a cross rod, said cross rod being adapted to seat in either of said bearings, a blade holder pivotally mounted between said arms, a blade carried by said holder.

5. A razor including a handle formed with spaced bearings, a head carried by one end of the handle whose outer surface is convex, spaced fingers carried by one edge of the head, spaced hooks carried by the other edge of the head, a frame formed with side arms and a cross rod, said cross rod being adapted to seat in either of said bearings, a blade holder pivotally mounted between said arms, a blade carried by said holder, said head having end notches provided to receive said arms and lock the blade edge in engagement with said hooks.

6. A razor including a handle, a head carried by one end thereof whose outer side is convex, a frame carried by the handle, a blade holder mounted in the frame, a blade in said holder, said frame being adjustable into two positions relative to the handle, hooks carried by one edge of the head, said frame, when in one position being adapted to swing back and forth relative to the head, and when in its position being adapted to hold the blade edge in engagement with said hooks.

In testimony whereof I have signed my name.

BUFORD J. STEEN.
